(57) **CLAIM**

I claim the ornamental design for an illuminated address panel, as shown and described.

DESCRIPTION

FIG. 1 is a perspective view of an illuminated address panel, showing my new design;

FIG. 2 is an exploded perspective view thereof;

FIG. 3 is a front elevational view thereof;

FIG. 4 is a rear elevational view thereof;

FIG. 5 is a left-side elevational view thereof, the right-side elevational view being a mirror image thereof; and,

FIG. 6 is a top plan view thereof, the bottom plan view being a mirror image thereof.

The broken lines showing an address sheet in FIGS. 1 and 2 and mounting hardware in FIG. 3 depict environmental matter and form no part of the claimed design.
